United States Patent Office

Des. 208,177
Patented July 25, 1967

208,177

OVEN

Robert G. Wilson, 643 E. Faris Road,
Greenville, S.C. 29605

Filed Dec. 3, 1965, Ser. No. 47

Term of patent 14 years

(Cl. D81—10)

Fig. 1.

Fig. 2.

The dominant features of the design are shown in full lines.

I claim:

The ornamental design for an oven, substantially as shown and described.
